UNITED STATES PATENT OFFICE.

FREDERICK G. JAHN, OF NEW YORK, N. Y., ASSIGNOR TO THE INTERNATIONAL POSTAL SUPPLY COMPANY OF NEW YORK, OF BROOKLYN, NEW YORK, A CORPORATION OF NEW YORK.

FEEDING MECHANISM.

No. 856,847.

Specification of Letters Patent.

Patented June 11, 1907.

Application filed October 25, 1905. Serial No. 284,292.

To all whom it may concern:

Be it known that I, FREDERICK G. JAHN, a citizen of the United States, residing at the borough of Brooklyn, city of New York, county of Kings, and State of New York, have invented certain new and useful Improvements in Feeding Mechanism, of which the following is a specification.

The present invention relates generally to feeding mechanism adapted to feed single pieces of paper or other material or mail matter and the like in succession from a pile, stack or bunch thereof.

It has for its object to provide a simple and inexpensive mechanism adapted without adjustment to efficiently operate on uniform and non-uniform matter or material with equal facility; and furthermore to improve the general construction of the mechanism, and to render certain of its parts subject to wear easy of substitution.

As a better understanding of the improvements will be had from a detailed description of a practical embodiment thereof such description will now be given in connection with the accompanying drawings, in which:

Figure 1, is a plan view of the improved mechanism associated with a portion of a printing mechanism of well known type. Fig. 2, is a sectional side elevation of a portion of the feeding mechanism. Fig. 3, is a sectional end elevation thereof. Fig. 4, is a horizontal section on the line 4 of Fig. 2. Fig. 5, is a perspective view of the wiper, removed from its place. Figs. 6 and 7 are vertical sections on the lines 6 and 7 respectively of Fig. 2.

The improved feed mechanism A, is shown associated with a printing couple B, and accompanying parts as usually arranged in a well known type of post office mail matter marking machine, and of the character illustrated in my United States Letters Patent, No. 657,939, dated September 18, 1900, simply by way of illustrating an embodiment of the invention to practical purposes.

The printing couple consists of the usual die or printing roller 15 and impression roller 16 with which is associated a pair of feed rollers 13, 14 and a trip finger 205 for controlling the rotation of the printing roller in a manner similar to that set forth in my said Letters Patent.

The feed mechanism A consists of a feed roller 12 carrying a rubber feed surface 12^a

with which may be associated a supplemental and smaller feed roller 11, also having a rubber feeding surface 11^a. Opposed to the feed roller 12 is the improved wiper-separator by which the feed of single pieces is insured. This consists of a flexible wiper 50 and a bearer 30 arranged one in advance of the other to bear against the feeding surface of the feed roller in the manner indicated in Fig. 1.

The bearer and wiper are carried by a supporting guide or plate 3 secured through an intermediate block 6 to a post 5 which rises through a hole in the machine base C from one end of an arm 4, that is hung on a pivot 2 carried in said machine base; the construction adapting the bearer and wiper to move or yield bodily away from the feed roller against the tension of a suitable spring 18, to accommodate the feed of different thickness of matter through the machine.

The supporting guide or plate 3 extends, in the main, parallel with and along one side of the path of movement of the pieces passing from the feed mechanism to the printing couple, the opposite side of said path being guarded by a fixed guide 28. At the entrance to the feed mechanism the guide or plate 3 is bent outwardly to provide a flared entrance for the material passing between the wiper and feed roller. This bent portion of the supporting plate forms an angularly arranged or inclined seat for the wiper 50 so that the tendency of the wiper is to occupy the position shown in Fig. 4, but which, owing to its flexibility, will, in bearing against the feed roller, have its free end bent inwardly toward the supporting plate as in Fig. 1.

The wiper 50 is preferably a rectangular piece of rubber of suitable thickness and backed with canvas or other material 55, to prevent it from stretching, with a central hole 10, adapting it to engage a fixed stud 1, projecting from the angular or inclined seat provided by the supporting plate 3, see Fig. 4. Between the angular seat of the guide or plate 3 and the back of the rubber is interposed a distance piece 7 whose particular function is to form a space in rear of the forward free end of the wiper, Figs. 1 and 7, so that when the latter is in use its end may yield slightly with respect to the supporting guide or plate. The distance piece 7 is formed with flanges 8 to engage the opposite

edges of the wiper to keep it in proper alignment, and its outer inactive end is guarded and partially overlaid by the bent end of a plate 9 which may extend outwardly at right angles to the direction of feed of the material to form a guide therefor to the flared entrance for said material. The flanges 8 and bent end of the plate 9, Figs. 4 and 6, form a pocket to receive and protect the outer end of the wiper 50. As the flexibility of the substance of the wiper may not be sufficiently lasting, the wiper may be backed up by a slender spring or springs 17, Figs. 4, 6, and 7, the outer ends of the springs 15 being guarded by a shoulder on the bearer 30.

In the preferred construction the wiper 50 has its hole 10 centrally arranged therein so that, after its one end has become worn, it may be removed from its stud 1 and changed 20 end for end and replaced with its worn end extending into the pocket behind the end of the plate 9.

The bearer 30 and wiper 50 are of the same widthwise dimensions as the rubber feeding 25 surface of the roller 12, so that the wear thereon will be uniform; and the bearer may extend along in the direction of the length of the guide or plate 3 as indicated in the drawings, or it may be a simple rectangular block 30 of narrow dimensions, of a size sufficient to bear upon the feed roller, its function being to exert enough pressure on the passing matter as to cause the feed roller to carry it onward.

35 The spring 18 may be any suitable form. As shown, one of its legs is supported by a short stud 20 in the machine table and the other engages the supporting post 5, and may be easily removed.

40 In operation, a bunch or stack of the matter to be fed through the machine is arranged vertically on edge with the forward ends directed toward and entered slightly into the flared end of the feed mechanism with the 45 outermost piece bearing with a gentle pressure against the feed roller 12 and 11, but mainly exerted against the roller 12. The rotation of the feed rollers carries the piece 50 onward into the bight between the roller 12 and the wiper 50, past the wiper, thence between said roller and the bearer 30, to the feed rollers 13, 14 and forward into the printing couple. Owing to the position and arrangement of the wiper 50, only one piece at 55 a time will be permitted to be fed forward, the surface of the wiper interposing sufficient friction to the forward ends of the succeeding pieces to prevent their forward movement while the first piece is being fed 60 by the roller 12. As soon as the tail of the first piece of matter has passed beyond the forward end of the wiper the next succeeding piece will be forwarded by the feed roller 12.

The desired space between succeeding pieces 65 of matter may be governed by the relative

surface speed of the rollers 13 and 14 with that of the roller 12.

While the improvements are shown in connection with a machine adapted to forward the pieces of matter therethrough, vertically 70 on edge, it is obvious that they are equally applicable to the horizontal forwarding of the pieces.

A flexible wiper and a bearer both impinging against the surface of a feed roller 75 are illustrated and claimed in a companion application for Letters Patent filed by me August 16, 1905, Serial No. 274,447, but the wiper and bearer herein described differ therefrom in the improved construction and 80 arrangement shown and herein claimed.

What is claimed is:

1. The combination with a feed device, of a yieldingly mounted guide providing an inclined seat and a bearing block, and a flexible wiper supported on said seat with its free end and the bearing block arranged to impinge against a moving surface of the feed device.

2. The combination with a feed device of a yieldingly mounted guide providing bearing block and an inclined seat with a stud, and a flexible wiper supported on said seat and mounted on said stud with its free end and the bearing block arranged to impinge against a moving surface of the feed device.

3. The combination with a feed device, of a yieldingly mounted guide providing an inclined seat and pocket or guard and a bearing block, a flexible wiper supported on said seat and extending into said pocket with its free end and the bearing block arranged to impinge against a moving surface of the feed device.

4. The combination with a feed device, of a yieldingly mounted guide providing a bearing block and an inclined seat with a stud, and a flexible wiper having a centrally arranged hole adapting it for reversal on said seat and stud with the free end of the wiper and the bearing block arranged to impinge against a moving surface of the feed device.

5. The combination with a feed device, of a guide providing an inclined seat and a bearing block, a flexible wiper supported on seat with its free end and the bearing block arranged to impinge against a moving surface of the feed device, and a spring carried by the guide and reinforcing the free end of the 120 wiper.

In testimony whereof, I have signed my name to this specification in the presence of two subscribing witnesses, this 23d day of October, 1905.

FREDERICK G. JAHN.
